KNITTED TRIMMING.

1,030,996.

Specification of Letters Patent.

Patented July 2, 1912.

Application filed March 2, 1912. Serial No. 681,288.

To all whom it may concern:

Be it known that I, SAMUEL N. GOODMAN, a citizen of the United States, residing at Philadelphia, county of Philadelphia, and 5 State of Pennsylvania, have invented a new and useful Improvement in Knitted Trim- mings, of which the following is a full, clear, and exact description, reference being had to the accompanying drawings, which form a 10 part of this specification.

The object of my invention is to produce a knitted trimming, more particularly of the specific class known as edgings for ladies' underwear, which shall have certain 15 advantages, both with respect to utility and to capacity for producing a different or more attractive appearance than edgings heretofore known.

In the ordinary edging of this class, the 20 same consists of a body and an ornamental design appended to one edge thereof. The body comprises the following elements: first a heading consisting of a longitudinally extending single or plural row of chain stitches (the several rows, where more than one row is used, being united by fine transversely extending threads), the same constituting the "sewing-on space"; second, a longitudinally extending single row of chain stitches, which adjoins the ornamental portion of the design and between which and the heading or "sewing-on space" is formed a "ribbon space" or "braiding space"; and 25 third, transversely extending "pillar bars" uniting the heading and single row of chain stitches adjoining the ornamental portion, said pillar bars being usually spaced apart and each comprising one or more threads. The construction is such as to permit a ribbon or braid to be retained in the ribbon space by passing it over and under alternate pillar bars. This ribbon, besides adding to the ornamental appearance, performs the 30 useful function of a "drawing string." That is, if, for example, the edging is placed around the neck, the wearer of the garment pulls the ends of the ribbon and ties them together, thus fastening the garment in place at the neck.

The ordinary edging has certain disadvantages, one of which is that the pillar bars have to be arranged fairly close together to permit the ribbon to be properly threaded through the ribbon space. Another disad-

vantage is that when the garment is in place, 55 one half of the pillar bars are concealed from view. Another disadvantage is that it requires considerable time to pass the ribbon over and under alternate pillar bars. Another disadvantage is that the edging 60 presents substantially the same appearance on both sides. Another disadvantage is that when the garment is worn, the ribbon contacts with the body of the wearer. In my invention all these disadvantages are 65 overcome. In knitting my improved edging I proceed in the ordinary way except that I form about one half the usual number of pillar bars and cover the ribbon space back of the pillar bars by knitting a fabric, preferably a fine web, the threads of which are, at the longitudinal edges of the fabric, knitted in with, and held in place by, the longitudinal rows of stitches bounding the ribbon space. The web consists preferably, but not necessarily, of the arrangement of stitches well known in the art as a "nubia" fabric. With such a construction, the ribbon is threaded between the pillar-bars on the 70 front and the web on the back, thereby facilitating the threading of it in place. The pillar-bars, as stated, may be arranged at twice the usual distance apart and yet present the same appearance, when the edging is viewed from the front, as if they were arranged the usual distance apart, or the pillar bars may be arranged the usual distance apart and present, when viewed from the 75 front, an appearance of being much closer together than in the ordinary edging, because none of them is concealed. Further, the edging presents entirely different appearances when viewed from front and back. Finally, the web on the back prevents the 80 ribbon or braid from contacting with the body of the wearer, which is an advantage of considerable importance.

In the drawings: Figure 1 is a plan view showing the appearance of the edging. Fig. 2 is a detail plan view of a part of the 85 edging shown in Fig. 1.

a and *b* constitute a double row of longitudinally extending chain stitches and *c* the fine threads uniting rows *a* and *b* and forming with them the heading or sewing-on space. The thread forming the web *c* is passed back and forth from one row *a* of 90 stitches to the other row *b*, being tied into

place by the loops of the chain stitches in the manner well known to those skilled in transverse-warp machines, upon which the edging is knitted.

5 *d* is the longitudinal row of chain stitches bounding the other edge of the ribbon space. In the particular fabric shown in the drawings, another row of chain stitches *e* (forming part of the ornamental border) is provided and the yarn *f* forming the pillar bars extends longitudinally from row *e* in a curved direction to row *d*, thence across the ribbon space to row *b*, thence back across the ribbon space to row *d*, and thence in a 10 curved direction longitudinally to row *e*, and so on in successive repeats, the said yarn being confined by the loops of the several chain stitches in the manner well known in the art. In the particular fabric shown 15 20 in the drawings, still another row of chain stitches *g* (forming the outer margin of the ornamental border) is provided, said chain extending longitudinally in a series of scallops. Loops *h* extend inwardly from the 25 chain *g* at the intersection of successive scallops and are confined by the loops of chains *e* and *d*.

The knitted web *i* is composed of fine threads looped together in the manner well 30 known to knitters of nubia, the edges of the web being bound in by the loops of the chains bounding the ribbon space.

k represents a ribbon which, as shown, is passed between the pillar bars *f* and the 35 knitted web *i*.

That portion of the particular fabric hereinbefore described which lies outside the chain *d* forms no part of the invention and is simply shown because the yarn forming 40 the pillar bars constitutes part of the design of this portion of the fabric. It will be understood that this ornamental portion of the fabric may be varied as described, and

that the arrangement of transverse threads across the ribbon space may also be varied 45 as desired.

Having now fully described my invention, what I claim and desire to protect by Letters Patent is:

1. An edging for underwear, etc., comprising two longitudinally extending rows 50 of stitches forming between them a ribbon space, transverse threads uniting said rows, and a knitted web also uniting said rows and forming between it and the transverse 55 threads a ribbon-retaining pocket.

2. An edging for underwear, etc., comprising a longitudinal plural row of stitches forming a heading, another longitudinal row of stitches, transverse threads uniting 60 the last named row and one of the first named rows, and a knitted web uniting the same two rows, whereby a ribbon may be passed between the transverse threads and the web. 65

3. An edging for underwear, etc., comprising one or more longitudinal rows of chain stitches forming the heading or sewing on space, cross threads uniting said rows, a longitudinal row of chain stitches 70 widely spaced from the said heading and forming between them a ribbon space, a knitted web extending across the ribbon space, and threads extending across the ribbon space and overlying the web and spaced 75 apart to form pillar bars, said web and pillar bar threads being united to the chain stitches bounding the ribbon space.

In testimony of which invention, I have hereunto set my hand, at Philadelphia, on 80 this 29th day of February, 1912.

SAMUEL N. GOODMAN.
